HEEL-ATTACHING MACHINE

Thomas H. Seely, Melrose, Mass., assignor to
 United Shoe Machinery Corporation, Flemington, N. J., a corporation of New Jersey

Application April 21, 1941, Serial No. 389,547

35 Claims. (Cl. 12—42)

This invention relates to machines for attaching heels to shoes, and especially to those in which a shoe and heel are clamped together upon a support, and then subjected to the action of a tool or tools for effecting the insertion of a screw through a passage in a last within the shoe and through the heel-seat into the heel.

An object of the invention is to effect the clamping of the work by means which gives the operator free access to it, and which applies the clamping pressure effectively and in a manner which may be varied for work of different forms. With this in view, I combine with a support for a lasted shoe and a heel, and a tool for operating thereon, a work-clamping device, which may include a lever, movable into engagement with the last of the work upon the support and thereupon extending upwardly and rearwardly from said last, and a mounting joining the member to the machine-frame and situated above the support. With this arrangement, the clamping member in its active position is entirely removed from the field in which the operator must manipulate the work. As herein disclosed, to the lever of the work-clamping mechanism are pivotally connected two arms, also pivoted to the machine-frame, one being joined to the lever through a link. This link and the arm joined to it furnish a toggle, through the straightening of which the clamping lever may be actuated. The direction of approach of the clamping member to the work is preferably altered by changing the pivotal connection of the link to the lever. To enable the operator by depression of a treadle to first move the clamping member quickly into engagement with the work, and thereafter to apply a relatively heavy clamping pressure, two levers are fulcrumed upon the treadle and are yieldably urged toward each other, as by a connecting spring. The treadle also carries clutch mechanism, and two links join the clamping mechanism to the clutch mechanism and to one of the levers. The other lever has means for producing engagement of the clutch mechanism with its link. Through the two links, the work-approaching and pressure-applying actions of the clamping mechanism are effected. Such an actuating arrangement is simple, compact and calls for little adjustment.

In machines of this character, it is customary to cause a driven tool or tools, which are to operate upon the work, to act only with a predetermined force. This may be for the purpose of preventing a heel-attaching screw from being set too hard, so the thread formed in the heel might

be stripped. Another object of my invention is to free a tool from its driving means by effective mechanism, accurate in its response to the chosen releasing force. About a driving shaft, a sleeve is rotatable and is connected to the tool, there also being a clutch-disk rotatable about the shaft and co-operating with a clutch member carried by said shaft. The disk and sleeve are compelled to rotate together while moving relatively longitudinally of the shaft, and have a spring or other means for forcing them yieldably together toward each other. Movable longitudinally of the shaft is means for varying this force, as by a screw extending through the end of the shaft, convenient for adjustment by the operator. That the resistance offered by the clutch-elements to release may be uniform, they are constantly lubricated from a receptacle which surrounds said elements and is rotatable with the clutch. To this receptacle, the lubricant may be supplied during rotation through an opening in a surrounding stationary casing. With the clutch-elements arranged as just indicated, the receptacle is preferably carried by the sleeve connected to the tool. Any excess of lubricant supplied to the receptacle may be collected in a depression in the casing, and discharged through an opening therein.

Since the rotation of the shaft through which the tool is driven may endanger the operator by contact with it, an object of the invention is to properly protect this. To this end, it is guarded by a surrounding sleeve formed of intermeshing oppositely placed helices. The guard is flexible, may be made resistive to distortion, and by forming the helices under a stress tending to contract them, the weight of the parts is partially counterbalanced.

A further object of the invention is to so mount certain mechanisms of the machine, that they are situated conveniently for the particular operator by whom they are to be used, and so they shall properly co-operate with each other. For the attainment of this object, a column is movable vertically in the machine-frame, said frame carrying the work-support. Work-clamping mechanism and an operating tool are mounted together upon the column for co-operation with the support. The clamping mechanism and tool are thus simultaneously adjustable as to height, as for the purpose of locating the clamping mechanism for proper engagement with the work upon the support. The work-support may be positioned vertically upon the frame as desired by the operator. I have herein shown a member car-

ried by the frame and upon which the column rests, together with means arranged to raise and lower the member. When the column is adjusted in this manner, it is desirable that it shall not disturb the normal position of the treadle, because of its connection to the clamping mechanism carried by the column. One of a series of connecting members between the treadle and clamping mechanism is, therefore, movable upon the frame, and another upon the column or other mounting member for the clamping mechanism. The member upon the frame is unaffected by the adjustment, and the companion member may be so related as to be little disturbed. I prefer to employ in the connections two levers, one fulcrumed upon the frame and the other upon the mounting member, and to connect these two levers by a substantially horizontal link.

In the accompanying drawings illustrating a particular form of the invention,

Fig. 1 shows the upper portion of my improved machine in side elevation, with parts broken away;

Fig. 2 is a similar view of the lower portion of the machine;

Fig. 3, a vertical section through one of the driving clutches taken in a plane from front to rear of the machine;

Fig. 4, a front elevation of the work-clamping elements;

Fig. 5, a broken side elevation of such elements in their normal positions; and

Figs. 6 and 7, full horizontal sections on the lines VI—VI and VII—VII, respectively, of Fig. 3.

In many respects the present apparatus resembles that of Letters Patent of the United States No. 1,826,723, Bertrand, October 13, 1931. In this, a shoe S upon a last L is situated right-side-up, and, with a heel H in place beneath the heel-seat, is held upon a support A by clamping mechanism B actuated by treadle mechanism C. Here, it is subjected to the action of drilling mechanism D for operating a drill d through a passage in the last to make a hole through the heel-seat of the shoe into the heel. Thereafter, a temporary screw s is inserted in the hole through the last-passage by driving mechanism E, until the head of the screw acting against the crown of the last-cone draws the cup of the heel firmly against the heel-seat, to retain it until an interposed adhesive has set.

A frame 10 furnishes at the top a table 12, through which passes a spindle 14, which may be clamped in different vertical positions by a set-screw 16. A vertical bore in the upper extremity of this spindle receives a stem 18 upon the work-support A, which may be fixed at different heights by a set-screw 20. Both the spindle and stem are shown spotted to assure proper retention by the set-screws, those for the stem being more closely spaced. Thus, a coarse and fine adjustment of the work-support is provided, which is employed for both varying the position at which the work is engaged by the clamping mechanism D and the level of said work for the convenience of the operator. The support A has a tread-rest 22 for the shoe and heel, the angle of which may be altered by an adjusting wedge 24, and there is a back-stop 26 for the heel, this being variable in height.

Through a vertical bore in an enlargement 28 at the rear of the table passes a tubular column 30. Upon this are clamped by screws 32 brackets 34 and 36, these, respectively, carrying the clamping mechanism B and the drilling and screw-driving

mechanisms D and E. At the bottom, the column rests upon a base-piece 38, below which is a collar 40, supported by a nut 42 threaded upon the lower extremity of a rod 44 rising through the column. The hooked upper end 46 of the rod passes through a slot in the column, and lies in a depression in the top of the enlargement 28. By turning the nut 42, the base-piece and column may be lifted together or allowed to descend to locate the clamping mechanism and the drilling and driving mechanisms at different levels. Having set the work-support A at a height chosen by the operator, by the screws 16 and 20, adjustment of the column will position the clamping mechanism to properly approach and engage the last-cone to hold the work for the operations upon it. In the latter respect the adjustment of the work-support also may be utilized, the screw 20 giving a fine adjustment.

The clamping mechanism B has a cross-rod 50, extending between the lower extremities of two spaced side-pieces of a lever 52 and arranged to bear upon the crown of the cone of the last L. At their upper ends, the side-pieces are joined by a rod 54 (Fig. 4). The lever 52 has a floating fulcrum-pin 56, which pivotally connects an upper link 58 to a lower arm 60 made up of spaced side-pieces pivoted at 62 upon the bracket 34. The link 58 is pivotally joined at 64 to an arm 66, which is in turn pivoted at 68 upon the bracket 34. A slot 70 in the lever 52 may be shifted along the fulcrum-pin 56, it being located at predetermined points by a cross-pin 72, which is engaged by any one of a series of pairs of depressions 74 in the sides of the lever 52. In the selected depressions, the pin 72 is retained by a pair of tension-springs 76, 78, connecting the pivot-pins 64 and 66. To an extension from the arm 66, near its center, a rod 78 is joined. At the threaded lower extremity of the rod, supported upon a nut and lock-nut 80, is a compression-spring 82. Upon the upper end of the spring rests a collar 84, loose upon the rod and engaged by a cross-pin 86 extending through a slot in said rod and connecting the spaced arms 88 of a bell-crank-lever 90. Another arm 92 of the lever projects upwardly, and is joined by a link 94 to one arm of a bell-crank-lever 96 fulcrumed beneath the table 12. From a second arm of the lever 96, rods or links 98 and 99 lead to the treadle mechanism C.

The elements of the clamping mechanism B are initially related as appears in Fig. 5 of the drawings. The arm 66 is prevented from swinging rearwardly past the vertical position by a stop-screw 100, threaded into the arm and contacting with the column 30. After the work has been placed upon the support A, actuation of the treadle mechanism draws down the rod 78. This straightens the toggle, formed by the arm 66 and the portion of the link 58 above its pin 72, and lowers the lever 52, the rod 50 engaging the crown of the last-cone. This is as shown in Fig. 1. The path followed by the rod 50 is indicated by the upper curved dash line (Fig. 5) joining its extreme positions. This is with the cross-pin 72 in the lowest pair of depressions 74 in the lever 52. As the lasts and heels vary in form, the pin may be transferred to depressions which will cause the rod 50 to take one of the other paths indicated. This is to cause the pin to engage the crown of the last at such a point, that pressure will be applied most effectively to force the heel-seat of the shoe against the cup of the heel. In each case, there is exerted a pressure which is not only downward, but has also a component acting toward the rear of the work. This en-

sures that the heel will be held firmly against the back-stop 26. It is to be noted that the elements of the clamping mechanism B are above the work in all positions and that the lever 52 is withdrawn upwardly and rearwardly therefrom, giving the operator access to it wholly without interference.

Considering now the mechanism C through which the clamping mechanism B is actuated, there is fulcrumed at 110 at the bottom of the frame a treadle 112, having connecting its spaced side-arms a foot-pad 114 for depression by the operator. The treadle is held normally raised by a tension-spring 116, connected to the under-side of the table 12. It may be latched down to hold the work under clamping pressure by a foot-lever 118, fulcrumed at 120 upon the treadle and having a detent 122 engaging some one of a series of teeth 124, upon a segment 126 carried upon the frame. An expansion-spring 128 interposed between the treadle and the lever 118 urges the latching detent against the segment. Fulcrumed at 130 upon the treadle is a lever 132, compelled initially to move bodily with the treadle by a spring 134, which joins it to said treadle and acts to draw a projection 136 from its lower end against the fulcrum 120 of the latching lever. Fulcrumed at 130 with the lever 132 is a second lever 138, which at its outer extremity is held yieldably against the end of the lever 132 by a tension-spring 140 extending between them. The levers 132 and 138 are bowed outwardly from each other to receive the spring between them. At the rear of its fulcrum, the lever 138 has rotatable upon it a roll 142 for actuating clutch mechanism c, associated with the treadle-rod 99. A normally fixed block 144 of the clutch mechanism is pivotally mounted at 146 upon the treadle 112, and may be adjusted toward and from the lever-roll 142 by a contact-screw 148 threaded horizontally upon the treadle. Guided upon the stationary block 144 is a movable clutch-block 152, for engagement by the roll 142. The opposed faces of the clutch-blocks may be recessed vertically to receive between them an extension 154 pivoted at 156 upon the rod 99.

When the operator depresses the treadle 112 to bring the rod 50 of the mechanism B into engagement with the last in the shoe upon the support A, the roll 142 is so positioned that it does not exert clutching pressure upon the block 152, and the rod 99 is freely movable. The treadle, however, transmits movement through the lever 132, link 98, lever 96, link 94, lever 90, spring 82 and rod 78, to straighten the toggle-lever 66, 58 and carry the rod 50 into engagement with the last-crown, as has already been described. This is accomplished speedily, because the effective attachment of the link 98 to the treadle mechanism is close to the operator's foot. When the rod 50 rests upon the last-crown, the movement of all the elements joining it to the lever 132 stops, so the end of this lever at the link 98 is held against movement. Depression of the treadle continues, both the springs 134 and 140 expanding. The outer end of the lever 138 is separated from the end of the lever 132, and the counter-clockwise movement of the lever-fulcrum 130 (Fig. 2) causes the roll 142 and the clutch-block 152 to be forced together, urging said block toward the block 144 and clutching the rod-extension 154 to the treadle. The rod 99, through the chain of elements previously traced, applies relatively heavy pressure to the work, because of the ratio between the lever-arms formed between the

fulcrum 110 and the extension 154, and between said fulcrum and foot-pad 114. In its clamping position, the treadle is maintained by the detent 122, to be released when desired by depression of the latching lever 118. The tension of the springs 134 and 140 may be adjusted by screws 160, 160, threaded through the lever 132 and to which they are connected. Yield of the spring 140 limits the force which may be applied by the roll 142 to the clutch c. Variation in the position of the screw 148 allows the normal relation of the clutch to the roll to be adjusted. Since the clamping force is applied to the work through the loaded spring 82, the compressibility of this spring, determined by adjustment of the nuts 80, limits said force.

It is desirable that the normal height of the treadle 112, which may be varied to suit the operator by a terminal 162 threaded upon the link 98, shall remain constant, to whatever height the column 30 may be adjusted. Such a condition is attained by the actuating connections of this invention. The fulcrum of the lever 96 is fixed and, therefore, unchanged by the adjustments, while the vertical shift of the lever 90, fulcrumed through the collar 40 to move with the column and acting upon the substantially horizontal link 94, has little effect upon the lever 96. Therefore, any change in the height of the treadle, produced by movement of the column, is negligible.

Taking up the operating mechanisms D and E which, respectively, drill the work and insert a screw therein, these mechanisms are supported together upon the bracket 36 with a motor 170, by which they are driven. The mechanisms may be similarly mounted and operated, and only the screw-driving mechanism E will be described in detail. This mechanism E is carried by a casting 172, secured to the end of a stem 174 extending horizontally through an opening in the bracket 36 and secured adjustably by a set-screw 176. Journaled in the casing in an upper bearing 178 (Fig. 3) and a lower bearing 180 is a vertical shaft 182, there being a sleeve 184 fitting about the bottom of the shaft, between it and the bearing 180. The shaft is rotated by belt-gearing 186 from the motor-shaft, that of the mechanism E turning at a less speed than that of the mechanism D. The sleeve 184 is internally threaded at its lower extremity to receive an upper threaded portion of a universal joint 187. The lower portion of the joint has fast upon it the upper section of a telescopic extensible shaft 188, the lower section of which is united through a universal joint 190 (Fig. 1) to a short shaft 192. Secured in an opening in the bottom of the casing 112 about the shaft 188 and its universal joints is a guard-sleeve g, which prevents contact of the person of the operator, or of work-parts with the enclosed rotating elements of the machine. Attached to the lower extremity of the guard-sleeve is a collar 196, and separably connected to this collar by a bayonet joint 198 is a handle 200, arranged to be grasped by the operator and in which the shaft 192 turns. Outside the handle there is secured to the shaft 192 a chuck 202, of such form as to receive and compel the rotation of the head of the screw s to be inserted. The sleeve g is extensible with the shaft 188, its length varying therewith. It is preferably formed, as best shown in Fig. 3, of intermeshing oppositely placed inner and outer helical strips of sheet-metal 204 and 205, U- or channel-shaped in cross-section. These strips

are wound under a stress which causes the helices to contract longitudinally, and, therefore, to shorten the sleeve. This tendency at least partially compensates for the weight of the lower section of the shaft 182 and the elements which it carries, making it easier for the operator to manipulate the driven tool. Supports 207 are mounted for vertical and horizontal adjustment upon the bracket 34. By these, the tools of the mechanisms D and E may be held in inactive positions convenient for their taking and return by the operator.

It is desirable that the force exerted by the screw-driver or other tool shall be limited. This may be provided, for example, in order that the screw s shall be turned into the work with its head exerting a substantially definite heel-clamping pressure upon the last. Consequently, there is provided, between the driving shaft 182 and the driven sleeve 184, a clutch which will release when the proper force is exerted. Extending horizontally through a bore in the shaft above the sleeve is a cross-pin 206 (Fig. 3). Resting upon the pin is a disk 208, in the underside of which are depressions 210, 210 separated by 180°. The disk and sleeve are compelled to rotate together, while capable of independent vertical movement, by two pins 212 rising from the sleeve and extending into openings in the disk. This disk is urged into engagement with the cross-pin by a spring 214, interposed between said disk and a washer 216 of inverted cup-shape, upon which rest flat washers 218. To allow a variation in the force with which the spring 214 urges the disk 208 into engagement with the cross-pin 206, there is recessed into the upper washer a crossbar 220 movable vertically in a slot in the shaft 182. Guided in an axial bore in the shaft is a rod 222, bearing at its lower end upon the crossbar and having contacting with its upper extremity a screw 224 threaded axially into the shaft. The screw may be turned in either direction to lower or permit to be raised the rod, crossbar and washers, and thus the expansive effect of the spring varied. This will alter the force necessary to cause the cross-pin 206 to leave the depressions 210, and thereby the release of the clutch to stop the rotation of the tool.

To ensure that the force necessary to disengage the clutch shall remain constant, it is essential that the engaging surfaces of the cross-pin 206 and the disk 208 be uniformly lubricated. For this purpose, the sleeve 184 is extended upwardly at 226 about the clutching surfaces and outside the depending skirt of the washer 216 to furnish an oil-receptacle. The oil may be delivered to this receptacle, while it is rotating, through an inlet-pipe 228 opening through the upper or cover-portion of the casing 172. Flowing from the delivery-opening, the oil is directed by an annular drip-flange 230 upon the casing and a downwardly and inwardly inclined surface 232 at the upper side of an inwardly projecting flange 234 at the top of the receptacle. Over the surface 232, it flows through a narrow annular space between the flange and the washer 216. Within the receptacle, the oil is free to pass to the clutching surfaces through clearance spaces in the disk 208 about the driving pins 212. As the receptacle 228 rotates, the oil is thrown by centrifugal force to the outside in a circular body, which narrows as it rises and is retained by the flange 234. Any excess of oil which has been supplied will escape through the space between the flange and the washer 216, to be thrown outwardly against the

interior of the casing 172. The falling oil is directed by a lower external annular flange 236 upon the receptacle into a depression 238 near the bottom of the casing. As it gathers in the depression, the oil may escape through a pipe 240, leading through the bracket 36 into the column 30. Here, it may be collected in a receptacle. In introducing oil through the pipe 228, the escape through the pipe 240 serves as an indication of the sufficiency of the supply. The oil, which is thereafter retained within the receptacle 226, will properly lubricate the mechanism for a considerable period. With this normal charge of oil, the contracted space between the flange 234 and the washer 216 holds against escape the oil-vapor created by the movement of the elements within the receptacle.

In using the apparatus, the operator, placing the cup of the heel upon the heel-seat of a lasted shoe S, applies their tread-surfaces to the rest 22 of the support A. Between the heel-seat and the heel-cup, an adhesive has been applied. Depressing the treadle 112 of the mechanism C, the rod 50 of the clamping mechanism D, through the rod 98 and intermediate connecting elements, is brought upon the crown of the last L within the shoe. Continued actuation of the treadle separates the lever 138 of the treadle mechanism from the lever 132 the consequent movement of the lever-fulcrum 130 causing the clutching of the rod-extension 154 to the treadle between the blocks 144 and 152. Now, relatively heavy pressure, of a degree determined by the load which has been placed upon the spring 82, is applied to the work through the rod 99 and the same connections as for the rod 98, and the treadle is latched at 122, 124 to hold this pressure. Taking the constantly rotating drill of the mechanism D from its support 207 by its handle 208, the operator passes this drill through the last-passage to produce a hole in the heel-seat of the shoe and in the clamped heel. Returning the drill to its support, the operator places a screw s in the last-passage, and applies to its head the chuck 202 of the inserting mechanism E, manipulating this similarly to the mechanism D. When the chosen turning force upon the screw is exceeded, the cross-pin 206 in the driving shaft 182 leaves the depressions in the disk 208 to stop the rotation of the screw-driver, it clicking in and out of these and warning the operator that the insertion is completed. The chuck is therupon removed from the screw-head, and the mechanism E returned to its support, the work 55 now being unclamped by depressing the latching lever 118. The shoe with its temporarily attached heel is thus released by the mechanism B for removal from the support A.

Having described my invention, what I claim as new and desire to secure by Letters Patent of the United States is:

1. In a heel-attaching machine, a support for a lasted shoe and a heel to be attached thereto, a tool for operating upon the work, a work-clamping device including a lever movable into engagement with the last of the work upon the support and thereupon extending upwardly and rearwardly from said last, and a mounting for the lever situated above the support.
2. In a heel-attaching machine, a frame, a support for a lasted shoe and a heel to be attached thereto, said support being carried by the frame, a tool for operating upon the work through the last, a work-clamping member extending upwardly from said last, and a mounting

for the member joining it to the frame and being situated above the support.

3. In a heel-attaching machine, a frame, a support for a lasted shoe and a heel to be attached thereto carried by the frame, a tool movable upon the frame for operating upon the work, a clamping lever arranged for engagement with the last, an arm pivoted upon the frame and pivotally connected to the lever, a second arm pivoted upon the frame, a link pivotally connected to the second arm and to the lever and furnishing with said second arm a toggle-lever, and means for straightening the toggle-lever to render the clamping lever effective.

4. In a heel-attaching machine, a frame, a support for a lasted shoe and a heel to be attached thereto carried by the frame, a tool movable upon the frame for operating upon the work, a clamping lever arranged for engagement with the last, an arm pivoted upon the frame and pivotally connected to the lever, a second arm pivoted upon the frame, a link pivotally connected to the second arm and to the lever, and means connected to the second arm for actuating the clamping lever.

5. In a heel-attaching machine, a frame, a support for a lasted shoe and a heel to be attached thereto carried by the frame, a tool movable upon the frame for operating upon the work, a clamping lever arranged for engagement with the last, an arm pivoted upon the frame and pivotally connected to the lever, a second arm pivoted upon the frame, a link pivotally connected to the second arm and to the lever, means arranged to make the pivotal connection at different points along the lever, and means connected to the second arm for actuating the clamping lever.

6. In a heel-attaching machine, a frame, a support for a lasted shoe and a heel to be attached thereto carried by the frame, a tool movable upon the frame for operating upon the work, a clamping lever arranged for engagement with the last and provided with a slot and a series of depressions, an arm pivoted upon the frame and having a pivot entering the lever-slot, a second arm pivoted upon the frame, a link joined to the second arm and to the pivot of the first arm in the slot, a projection from the link which may be placed in any one of the lever-depressions, and means for actuating the clamping lever.

7. In a heel-attaching machine, a frame, a support for a lasted shoe and a heel to be attached thereto carried by the frame, a tool movable upon the frame for operating upon the work, a clamping lever arranged for engagement with the last and provided with a slots and a series of depressions, an arm pivoted upon the frame and having a pivot entering the lever-slot, a second arm pivoted upon the frame, a link joined to the second arm and to the pivot of the first arm in the slot, a projection from the link which may be placed in any one of the lever-depressions, and a spring joining the connection between the second arm and the link to the lever.

8. In a heel-attaching machine, a support for a lasted shoe and a heel to be attached thereto, a tool for operating upon the work, a work-clamping member movable against the last, a treadle, clutch mechanism carried by the treadle, a lever fulcrumed upon the treadle, a link connected to the clamping member and to the lever, a link connected to the clamping member and arranged for engagement by the clutch mech-

anism, a second lever fulcrumed upon the treadle and yieldably urged toward the first, and means carried by the second lever for producing engagement of the clutch mechanism with its link.

5 9. In a heel-attaching machine, a support for a lasted shoe and a heel to be attached thereto, a tool for operating upon the work, a work-clamping member movable against the last, a treadle, clutch mechanism carried by the treadle, a lever fulcrumed upon the treadle, a spring joining the lever to the treadle, a link connected to the clamping member and to the lever, a link connected to the clamping member and arranged for engagement by the clutch mechanism, a second lever fulcrumed upon the treadle, a spring joining the second lever to the first, and means carried by the second lever for producing engagement of the clutch mechanism with its link.

10 10. In a heel-attaching machine, a support for a lasted shoe and a heel to be attached thereto, a tool for operating upon the work, a work-clamping member movable against the last, a treadle, clutch mechanism carried by the treadle, a lever fulcrumed upon the treadle, a link connected to the clamping member and to the lever, a link connected to the clamping member and arranged for engagement by the clutch mechanism, a second lever having the same fulcrum as the first and yieldably urged toward it, and a roll rotatable upon the second lever for actuating the clutch mechanism.

15 11. In a heel-attaching machine, a support for a lasted shoe and a heel to be attached thereto, a tool for operating upon the work, a work-clamping member movable against the last, a treadle, clutch mechanism carried by the treadle, lever mechanism fulcrumed upon the treadle, a link connecting the clamping member to the lever mechanism, a link connected to the clamping member and arranged for engagement by the clutch mechanism, and means arranged to vary the position of the clutch mechanism with respect to the lever mechanism.

20 12. In a heel-attaching machine, a support for a lasted shoe and a heel to be attached thereto, a tool for operating upon the work, a work-clamping member movable against the last, a treadle, clutch mechanism pivoted upon the treadle, lever mechanism fulcrumed upon the treadle, a link connecting the clamping member to the lever mechanism, a link connected to the clamping member and arranged for engagement by the clutch mechanism, and a contact-screw threaded upon the treadle and engaging the clutch mechanism to turn it upon its pivot.

25 13. In a heel-attaching machine, a support for a lasted shoe and a heel to be attached thereto, a tool for operating upon the work, a work-clamping member movable against the last, a treadle, a plurality of successively effective links through which the treadle may act with different leverages upon the clamping member, and members including a loaded spring for connecting each of the links to the clamping member.

30 14. In a heel-attaching machine, a work-support, a rotatable tool co-operating therewith, a rotatable driving shaft, a sleeve rotatable about the shaft and connected to the tool, a clutch-disk rotatable about the shaft, a co-operating clutch member carried by the shaft, means for compelling the disk and sleeve to rotate together while moving relatively longitudinally of the shaft, and means for forcing the disk and co-operating clutch member yieldably together.

35 15. In a heel-attaching machine, a work-sup-

port, a rotatable tool co-operating therewith, a rotatable driving shaft, a sleeve rotatable about the shaft and connected to the tool, a clutch-disk rotatable about the shaft, a co-operating clutch member carried by the shaft, means for compelling the disk and sleeve to rotate together while moving relatively longitudinally of the shaft, means for forcing the disk and co-operating clutch member yieldably together, and means movable longitudinally of the shaft and arranged to vary such force.

16. In a heel-attaching machine, a work-support, a rotatable tool co-operating therewith, a rotatable driving shaft, a sleeve rotatable about the shaft and connected to the tool, a clutch-disk rotatable about the shaft, a co-operating clutch member carried by the shaft, pins projecting from the sleeve and engaging the disk, a spring surrounding the shaft, and means extending through the shaft for forcing the spring against the disk.

17. In a heel-attaching machine, a work-support, a rotatable tool co-operating therewith, a rotatable driving shaft, a spring surrounding the shaft, clutch members connecting the shaft and tool for engagement under the influence of the spring, a member extending transversely of the shaft and movable thereon to act upon the spring, and an adjusting member extending longitudinally of the shaft and engaging the transverse member.

18. In a heel-attaching machine, a work-support, a rotatable tool co-operating therewith, a rotatable driving shaft, a spring surrounding the shaft, clutch members connecting the shaft and tool for engagement under the influence of the spring, a member movable upon the shaft to act upon the spring, and an adjusting screw for the member extending through the end of the shaft.

19. In a heel-attaching machine, a work-support, a rotatable tool co-operating therewith, a rotatable driving shaft, a clutch through which the shaft drives the tool, said clutch releasing when the tool encounters a predetermined resistance, and a receptacle for a lubricant rotatable with the clutch.

20. In a heel-attaching machine, a work-support, a rotatable tool co-operating therewith, a rotatable driving shaft, a clutch through which the shaft drives the tool, said clutch releasing when the tool encounters a predetermined resistance, a receptacle for a lubricant rotatable with the clutch, and means through which the lubricant may be supplied to the receptacle during rotation.

21. In a heel-attaching machine, a work-support, a rotatable tool co-operating therewith, a rotatable driving shaft, a sleeve rotatable about the shaft and connected to the tool, a clutch connecting the tool and shaft, and a receptacle for a lubricant surrounding the clutch and carried by the sleeve.

22. In a heel-attaching machine, a work-support, a rotatable tool co-operating therewith, a rotatable driving shaft, a clutch through which the shaft drives the tool, said clutch releasing when the tool encounters a predetermined resistance, a receptacle for a lubricant rotatable with the clutch, and a stationary casing surrounding the receptacle and having an opening and means for directing into the receptacle the lubricant introduced through the opening.

23. In a heel-attaching machine, a work-support, a rotatable tool co-operating therewith, a rotatable driving shaft, a sleeve rotatable about

the shaft and connected to the tool, a clutch-disk rotatable about the shaft, a co-operating clutch member carried by the shaft, and a receptacle for the lubricant carried by the sleeve and extending about the clutch members.

24. In a heel-attaching machine, a work-support, a rotatable tool co-operating therewith, a rotatable driving shaft, a clutch through which the shaft drives the tool, said clutch releasing when the tool encounters a predetermined resistance, a receptacle for a lubricant rotatable with the clutch, and a stationary casing surrounding the receptacle and having an opening and means for directing into the receptacle the lubricant introduced through the opening, the casing further being provided with a lubricant-collecting depression and an opening through which the collected lubricant may be discharged.

25. In a heel-attaching machine, a work-support, a rotatable tool co-operating therewith, a rotatable driving shaft, a sleeve rotatable about the shaft and connected to the tool, a clutch connecting the tool and shaft, and a receptacle for a lubricant surrounding the clutch and carried by the sleeve, said receptacle having at its open side an inwardly extending lubricant-retaining projection.

26. In a heel-attaching machine, a work-support, a rotatable tool co-operating therewith, a rotatable driving shaft, a sleeve rotatable about the shaft and connected to the tool, a clutch connecting the tool and shaft, a receptacle for a lubricant surrounding the clutch and carried by the sleeve, said receptacle having at its open side an inwardly extending lubricant-retaining projection, and a member rotatable with the shaft and lying in proximity to the projection to form therewith a narrow passage for the lubricant.

27. In a heel-attaching machine, a work-support, a rotatable tool co-operating therewith, a rotatable driving shaft for the tool, and a guard-sleeve surrounding the shaft and formed of intermeshing oppositely placed helices.

28. In a heel-attaching machine, a work-support, a rotatable tool co-operating therewith, a rotatable driving shaft for the tool, and a guard-sleeve surrounding the shaft and formed of intermeshing oppositely placed helices which are under a stress tending to contract them longitudinally.

29. In a heel-attaching machine, a frame, a work-support carried thereby, a column vertically movable through the frame, means for securing the column at different heights, and work-clamping mechanism and an operating tool mounted upon the column for co-operation with the support.

30. In a heel-attaching machine, a frame, a work-support carried thereby, means arranged to vary the height of the work-support upon the frame, a column vertically movable through the frame, means for securing the column at different heights, and work-clamping mechanism and an operating tool mounted upon the column for co-operation with the support.

31. In a heel-attaching machine, a frame, a work-support carried thereby, a column vertically movable through the frame, means for securing the column at different heights, work-clamping mechanism mounted upon the column and co-operating with the support, a member carried by the frame and upon which the column rests, and means arranged to raise and lower the member.

32. In a heel-attaching machine, a frame, a work-support carried thereby, a column vertically movable through the frame, means for securing the column at different heights, work-clamping mechanism mounted upon the column and co-operating with the support, a rod supported by the frame and extending through the lower portion of the column, a member surrounding the rod and upon which the column rests, and a nut threaded upon the rod and supporting the member.

33. In a heel-attaching machine, a frame, a work-support carried thereby, a work-clamping member co-operating with the support, a mounting member variable in position vertically in the frame and upon which the work-clamping member is movable, a treadle, and a series of connecting members between the treadle and work-clamping member, one of said connecting members being movable upon the frame and another movable with the mounting member.

34. In a heel-attaching machine, a frame, a work-support carried thereby, a work-clamping member co-operating with the support, a mount-

ing member variable in position vertically in the frame and upon which the work-clamping member is movable, a treadle, and a series of connecting members between the treadle and work-clamping member, one of said connecting members consisting of a lever fulcrumed upon the frame and another of a lever fulcrumed to move with the mounting member, with a substantially horizontal link connecting the levers.

35. In a heel-attaching machine, a frame, a work-support carried thereby, a column vertically movable through the frame, means for securing the column at different heights, work-clamping mechanism mounted upon the column and co-operating with the support, a member carried by the frame and upon which the column rests, means arranged to raise and lower the member, a lever arranged to be raised and lowered with the member, a lever fulcrumed upon the frame, a link connecting the levers, means for joining the first-mentioned lever to the work-clamping member, a treadle, and means for joining the second lever to the treadle.

THOMAS H. SEELY.

CERTIFICATE OF CORRECTION.

Patent No. 2,317,410.

April 27, 1943.

THOMAS H. SEELY.

It is hereby certified that error appears in the printed specification of the above numbered patent requiring correction as follows: Page 1, first column, line 22, for "active" read --inactive--; and second column, line 11-12, after the word "yieldably" strike out --together--; page 4, second column, line 75, claim 2, strike out "said" and insert instead --engagement with the--; page 5, first column, line 58, claim 7, for "slots" read --slot--; and that the said Letters Patent should be read with this correction therein that the same may conform to the record of the case in the Patent Office.

Signed and sealed this 6th day of July, A. D. 1943.

Henry Van Arsdale,
Acting Commissioner of Patents.
